APPARATUS FOR HEATING LIQUIDS WITH FLUID FUEL

William J. Handley, Jackson, Mich., assignor to Handley Brown Heater Company, Jackson, Mich., a corporation of Michigan

Application August 29, 1935, Serial No. 38,443

15 Claims. (Cl. 122—14)

This invention relates to a method of and apparatus for heating liquids with fluid fuel, and has to do particularly with an extremely simple, inexpensive heater unit and the manner of transferring heat units to liquid to be heated whereby high efficiency and low gas consumption is obtained while at the same time eliminating condensation.

In the past, condensation has been generally looked at as a necessary evil and in attempts to obtain efficient heating and low gas consumption most efforts have been directed towards special designs of the liquid tank usually in connection with the application of heat internally of the mass of liquid to be heated; most of such structures have been very expensive, particularly as compared to the standard range boiler type of hot water heater. Some attempts have been made towards inexpensive construction in that auxiliary attachments have been provided for standard range type boilers, but this has been usually with a sacrifice of efficiency and continued troubles with condensation.

It is my belief that these efforts in the past have tackled liquid heating problems from the wrong angle in that they have worked for increased efficiency by specially designed heating tanks and the like. The present invention contemplates the use of a simple cylindrical range boiler. It starts with the most inexpensive form and at the same time the most sturdy form of storage tank for the liquid to be heated, and an important feature of the present invention is that while such a simple inexpensive form of storage tank is used, I obtain an efficiency comparable to that of the most complicated and expensive type of heater. A second, and possibly more important feature of the present invention is that efficient heating is obtained with inexpensive equipment and the heat transfer carried out in such a manner that condensation is completely eliminated.

More specifically, I have found that if heating gases are applied on the outside of a storage tank and substantially all the heat units from such gases applied indirectly instead of directly to such tank, I obtain the utmost efficiency from such heating gases and without creating condensation. In fluid fuel heaters of the prior art, condensation has been one of the most difficult problems for the reason that heat, when directly applied to the cold surface, deposits moisture which obstructs and corrodes the exposed parts; this moisture absorbs injurious elements from the

flue gases, thus greatly increasing its corrosive quality.

In carrying out my invention I preferably utilize a low consumption burner and a relatively large storage tank, the heat transfer unit consists of vertical flues, spaced from the surface of the tank and enclosed within an insulating casing strapped on to the cylindrical tank in such a manner as to form an absorption chamber around the flues. Decrease in transfer of heat units by indirect heating instead of direct heating is compensated for by a reflecting surface forming a part of said absorption chamber and by forming the outer surface of the flues and effective surface of the tank of roughened black surfaces. Other features include structural details and other arrangements as will be more clearly set forth in the specification and claims.

In the drawings:

Fig. 1 is an elevation of a standard range boiler or domestic type of water tank.

Fig. 2 is an assembly view of the insulating casing, heating unit, consisting of combustion chamber, tubes and reflecting surface—ready to strap on the tank.

Fig. 3 is an elevation of the strap on assembly and range boiler.

Fig. 4 is a sectional view taken on line 4—4 of Fig. 3 illustrating the relative spacing of the boiler, combustion chamber, flue tubes, reflecting surface and insulation, and illustrating particularly the formation of the sealed absorption chamber.

Fig. 5 is a sectional view taken on line 5—5 of Fig. 4 showing the manner of securing the strap on assembly to the water tank and the internal arrangement of the burner and combustion chamber.

Fig. 6 is a fragmentary perspective view showing the strap on assembly support secured to the bottom of the tank.

A feature of the present invention is the fact that one of the important elements thereof is a standard domestic range or stand boiler as shown at 2. This boiler is not only important in that it embodies strength and cheapness but also in that it presents an ideal surface for my indirect non-condensation type of heating, as will be presently described. In carrying out this method of heating, a vertical portion of the range boiler is painted black as at 3 and preferably roughened. A clamp-on support 4 is secured to the bottom of the tank, as best shown in Figs. 5 and 6, this support being provided with a laterally extending supporting surface 5 for receiving a strap on

assembly. Painting of the tank and the clamping in place of the supporting device 4 is all that is necessary to be done to the standard domestic tank in preparing the same for receiving the 5 strap on heating unit.

This strap on heating unit may be generally designated 6, and is best shown as a unit ready to be strapped on in Fig. 2. This strap on unit consists of a sheet of insulation 7 split as at 8. It 10 may be molded to the general shape shown in Fig. 4 or may be held in such general shape by clamping straps. The outer surface of the insulation may be ornamental in appearance and the insulation held as a jacket around the tank 2 by 15 a sheet metal shell held together at the split by suitable fastening means.

Preferably secured to and forming a part of the interior surface of the insulating jacket is a mirror unit 11, formed of polished metal and 20 preferably consisting of a front flat surface 12 and two angularly extending wing members 13. When the insulating jacket is strapped into place, the wing members 13 are substantially normal to and contact with the arcuate surface of the boiler 25 so as to form an absorption chamber which may be designated 14.

Also secured to the mirror or reflecting member 11, by means of a bolt 15, is a combustion chamber 16, this combustion chamber being directly supported by the ledge 5 of the support member 4, thus while the sheet metal shell or strap members 9 would probably hold the insulating jacket and the strap on heating unit as a whole in place, the main function of the 30 shell or strap members is to hold the insulation as a jacket around the boiler and form the absorption chamber 14, and the entire strap on unit is mainly supported by the support member 4; although it will be seen that if the support member should become loose the entire strap on unit would still be held in place. A layer 17 of high temperature asbestos is positioned behind the reflector member 11. As will be later explained, the reflector is the medium for effecting 35 a great amount of heat transfer, thus additional insulation is provided for backing the reflector as well as the absorption chamber 14 as a whole.

A burner box 18 is carried by the combustion chamber 16, and preferably contains a low consumption burner unit 19. A standard thermostatic (not shown) may be used to control the flow of gas to the burner unit 19, so that the flame issuing from the burner and into the combustion chamber may be relatively low or a pilot flame, once the tank of water reaches a predetermined temperature, or may be in wide open full position, but still low consumption. Flue tubes 20 extend from the top of the combustion chamber, vertically through the absorption chamber 14, and out through the top, as best shown in Figs. 2 and 3. Top and bottom plate members 21 preferably seal the heating chamber at the top and bottom, respectively, so that the heating chamber 14 is substantially a 45 dead air space. After strapping on the unit, any cracks or openings between the plates may be sealed. The outside surface of the tubes 20 are roughened and black. Thus the roughened 50 dark surfaces of the flue tubes lose or transfer heat faster by radiation while the black surface of the tank absorbs heat faster than a relatively light smooth surface.

It will thus be seen that I have provided a 55 strap on heating unit for new or old range boil-

ers of such construction that products of combustion are completely isolated so there could not possibly be any comingling of the moisture between any moisture and such gases. The heating of the tank is completely indirect, and by radiation, convection and reflection; and as there is no direct application of heat to the tank at any time, it is obvious that there can be no condensation because of any heat from the heating unit; and inasmuch as the absorption chamber is a dead air space, it will be seen that condensation from any source will be prevented.

Efficient heating of the water in the tank 2 will first of all depend upon the quantity of water and the rapidity of heating desired, one or a 15 plurality of tubes 20 may be used but in every case all the products of combustion are conducted away from the combustion chamber 16 by such flues and will more than compensate for the indirect heating by the combination of 20 the reflector surface and the blackened surfaces on the tubes and the portion of the tank utilized to form one wall of the absorption chamber. Heat transfer from the tubes to the tank will be by radiation, reflection and convection, greatly 25 assisted by the black surface of the flues and the tank, and a portion of the heat reflected back against the black surface of the tank by the reflector 11. The size and number of tubes 20 are proportioned relative to the low consumption 30 burner unit and the rapidity of heating so that practically all the heat units from the products of combustion are absorbed by the tank in the travel of such products of combustion from the bottom to the top of the flues.

Although the absorption chamber 14 is a dead air space, circulation of air will take place because of the natural thermo-siphon action; furthermore, the greatest transfer of heat units between the absorption chamber and the tank will 40 take place at the localized point where there is the greatest differential in temperature. Thus if, for instance, sufficient hot water should be used to set up a band of cold water at the bottom of the tank, it will be seen that the greatest 45 transfer of heat units between the absorption chamber 14 and the tank will be at such band of cold water; or if all the water in the tank is substantially the same temperature, the transfer of heat units will be evenly distributed 50 between the absorption chamber and the surface of the tank.

As an illustration of the importance of the blackened surfaces of the tank, the tubes, and the reflector surface, complete tests made on the same tank and the same strap on heating unit, one with the blackened surfaces of the tank, the blackened surfaces of the tubes and a reflector surface, and the other without these blackened surfaces and without the reflector surface, showed 55 a 22% saving in gas consumption of the first set up over the second.

It will be understood that the combustion chamber may be of any type, size or shape as long as the main transfer of heat units is indirect; also that the strap on unit is particularly important for strapping on to and converting old 60 boilers into efficient heating units.

What I claim is:

1. Conversion water heating apparatus for domestic range boilers, comprising an insulating means surrounding at least a part of the boiler, a portion of the insulating means being spaced from the boiler to form an absorption chamber, fluid fuel combustion means positioned adjacent 70

the bottom of said absorption chamber, one or more flues conducting the products of combustion from said combustion means up through said absorption chamber, said flue or flues being spaced from the tank whereby the application of heat between the source of heat and the tank is indirect.

2. Conversion water heating apparatus for domestic range boilers, comprising an insulating means surrounding at least a part of the boiler, means extending along an outer wall of and being spaced from the boiler to form an absorption chamber, fluid fuel combustion means positioned adjacent the bottom of said absorption chamber, one or more flues conducting the products of combustion from said combustion means up through said absorption chamber, said flue or flues being spaced from the tank whereby the application of heat between the source of heat and the tank is indirect, the top and bottom of said absorption chamber being substantially sealed whereby to form a substantial dead air space around said flues.

3. Conversion water heating apparatus for domestic range boilers, comprising an insulating means surrounding at least a part of the boiler, means extending along an outer wall of and being spaced from the boiler to form an absorption chamber, fluid fuel combustion means positioned adjacent the bottom of said absorption chamber, one or more flues conducting the products of combustion from said combustion means up through said absorption chamber, said flue or flues being spaced from the tank whereby the application of heat between the source of heat and the tank is indirect, the top and bottom of said absorption chamber being substantially sealed whereby to form a substantial dead air space around said flues, a portion of the wall of said absorption chamber consisting of a reflecting surface.

4. Conversion water heating apparatus for domestic range boilers, comprising an insulating means surrounding at least a part of the boiler, a portion of the insulating means being spaced from the boiler to form an absorption chamber, fluid fuel combustion means positioned adjacent the bottom of said absorption chamber, one or more conduits conducting the products of combustion from said combustion means up through said absorption chamber, said conduit or conduits being spaced from the tank whereby the application of heat between the source of heat and the tank is indirect, the top and bottom of said absorption chamber being substantially sealed whereby to form a substantial dead air space around said conduits, the surfaces of said conduit or conduits and the adjacent surface of said tank being blackened to assist in the radiation and absorption of heat units.

5. Conversion water heating apparatus for domestic range boilers, comprising an insulating means surrounding at least a part of the boiler, a portion of the insulating means being spaced from the boiler to form an absorption chamber, fluid fuel combustion means positioned adjacent the bottom of said absorption chamber, one or more conduits conducting the products of combustion from said combustion means up through said absorption chamber, said conduit or conduits being spaced from the tank whereby the application of heat between the source of heat and the tank is indirect, the top and bottom of said absorption chamber being substantially sealed whereby to form a substantial dead air space

around said conduits, a portion of the wall of said absorption chamber consisting of a reflecting surface, the surfaces of said conduit or conduits and the adjacent surface of said tank being blackened to assist in the radiation and absorption of heat units.

6. Conversion water heating apparatus for domestic stand boilers, comprising an insulating means surrounding at least a part of the boiler, means extending along an outer wall of and being spaced from the boiler to form an absorption chamber, fluid fuel combustion means positioned adjacent the bottom of said absorption chamber, one or more conduits conducting the products of combustion from said combustion means up through said absorption chamber, said conduit or conduits being spaced from the tank whereby the application of heat between the source of heat and the tank is indirect, the top and bottom of said absorption chamber being substantially sealed whereby to form a substantial dead air space around said conduits, a portion of the wall of said absorption chamber consisting of a reflecting surface, the surface of said tank adjacent said conduits being blackened.

7. Conversion water heating apparatus for domestic sand boilers, comprising an insulating means surrounding at least a part of the boiler, means extending along an outer wall of and being spaced from the boiler to form an absorption chamber, fluid fuel combustion means positioned adjacent the bottom of said absorption chamber, one or more conduits conducting the products of combustion from said combustion means up through said absorption chamber, said conduit or conduits being spaced from the tank whereby the application of heat between the source of heat and the tank is indirect, the top and bottom of said absorption chamber being substantially sealed whereby to form a substantial dead air space around said conduits, a portion of the wall of said absorption chamber consisting of a reflecting surface, the surface of said tank adjacent said conduits being blackened.

8. A water heating apparatus of the storage, continuous supply type, comprising a storage tank and a heating unit comprising one or more conduits spaced from the tank and enclosing and conducting heating gases along the outside of said tank whereby the transfer of heat units from the heating gases to the tank is indirect, means for directing heat units radiated from said conducting means in a direction other than towards the tank back against the tank, said last named means cooperating with a portion of said tank to form an absorption chamber enclosing said conduit or conduits, and an insulating jacket surrounding said absorption chamber and clamped around said tank.

9. A water heating apparatus of the storage, continuous supply type, comprising a storage tank and a heating unit comprising one or more conduits spaced from the tank and enclosing and conducting heating gases along the outside of said tank whereby the transfer of heat units from the heating gases to the tank is indirect, means for directing heat units radiated from said conducting means in a direction other than towards the tank back against the tank, said last named means cooperating with a portion of said tank to form an absorption chamber enclosing said conduit or conduits, said absorption chamber being substantially sealed from the atmosphere to form a dead air space whereby transfer of heat

units from the absorption chamber to the tank will take place at a point or points of greatest temperature differential between the tank and the absorption chamber, and an insulating jacket 5 surrounding said absorption chamber and clamped around said tank.

10. A water heating apparatus comprising a container designed to hold a relatively large supply of water, a small consumption burner and a combustion chamber therefor positioned adjacent a wall of the container, one or more conduits forming a continuation of said combustion chamber and extending alongside of but spaced from the wall of said container whereby the transfer 15 of heat units from the conduit or conduits to the container is indirect, means surrounding said conduit or conduits and provided with a reflector surface for redirecting heat units radiated from said conduit or conduits back against the surface 20 of the tank.

11. A water heating apparatus comprising a container designed to hold a relatively large supply of water, a small consumption burner and a combustion chamber therefor positioned adjacent a wall of the container, one or more conduits forming a continuation of said combustion chamber and extending alongside of but spaced from the wall of said container whereby the transfer 25 of heat units from the conduit or conduits to the container is indirect, means surrounding said conduit or conduits and provided with a reflector surface for redirecting heat units radiated from said conduit or conduits back against the surface 30 of the tank, means clamped to the bottom of the tank and supporting said combustion chamber and conduit or conduits, and insulating means enclosing said conduit or conduits and the tank.

12. Conversion water heating apparatus for domestic storage tanks, comprising insulating 40 means surrounding at least a part of the tank, one or more conduits extending along side of but spaced from an outer wall of said tank, metallic enclosing means surrounding said conduit or conduits and forming an absorption chamber, and fluid fuel combustion means positioned adjacent 45 the bottom of the absorption chamber and so positioned that the products of combustion are conducted upwardly through said conduit or conduits, the transfer of heat units from the conduit 50 or conduits to the tank being indirect.

13. Conversion water heating apparatus for

domestic storage tanks, comprising insulating means surrounding at least a part of the tank, one or more conduits extending along side of but spaced from an outer wall of said tank, metallic enclosing means surrounding said conduit or conduits and having the ends thereof contacting with the tank and forming an absorption chamber, and fluid fuel combustion means positioned adjacent the bottom of the absorption chamber and so positioned that the products of combustion 10 are conducted upwardly through said conduit or conduits, the transfer of heat units from the conduit or conduits to the tank being indirect. 5

14. A water heating apparatus of the storage continuous supply type, comprising a storage 15 tank adapted to contain water and a heating unit positioned along a wall of said tank, fluid fuel combustion means positioned adjacent the bottom of said heating unit, one or more conduits positioned within said heating unit and spaced away from the wall of the tank, the fluid fuel combustion means being so located that the products of combustion thereof are conducted upwardly inside of said conduit or conduits whereby the transfer of heat units from the heating 20 unit to the tank is indirect, said heating unit cooperating with a wall of the tank to form an absorption chamber, said absorption chamber being substantially sealed from the atmosphere to form a dead air space whereby transfer of heat 25 units from the absorption chamber to the tank 30 will take place at a point or points of greatest temperature differential between the tank and the absorption chamber.

15. A strap-on heating unit for water storage 35 tanks and the like comprising, one or more conduits adapted to be positioned adjacent an outer wall of the tank, fluid fuel combustion means so positioned adjacent the bottom of said conduit or conduits that the products of combustion are conducted upwardly inside of said conduit or conduits whereby the transfer of heat units to the water in the tank is indirect, a metal enclosing member for said conduit or conduits having side portions adapted to contact with the walls of 45 the tank whereby to form a chamber around said conduit or conduits, and an insulated cover member adapted to be strapped around said metallic enclosing member and the water tank. 50

WILLIAM J. HANDLEY.
